UNITED STATES PATENT OFFICE.

ERNEST P. EVERETT, OF ASTORIA, NEW YORK.

MANUFACTURE OF BARRELS.

1,183,861.

Specification of Letters Patent. Patented May 23, 1916.

Application filed March 27, 1912. Serial No. 686,671.

To all whom it may concern:

Be it known that I, ERNEST P. EVERETT, a citizen of the United States, and resident of Astoria, Long Island, in the county of 5 Queens and State of New York, have invented certain new and useful Improvements in Manufacture of Barrels, of which the following is a specification.

This invention relates to the manufacture 10 of barrels or kegs.

The object of this invention is to produce a serviceable barrel or keg which may be very economically manufactured.

Many attempts have been made to produce 15 barrels of paper or of sheet metal to serve the purposes of the relatively expensive wooden barrels now in use. In Patent No. 947,629 of Jan. 25, 1910 granted to G. W. Norton and myself, we described the manufacture of a barrel having a wall of paper and formed directly from a web of "bilged" paper, that is, paper in the form of a web, the middle portion of which was extended or expanded so that the paper when coiled, 20 or rolled upon itself produced a bilged cylinder, that is, it would have the barrel form. In that patent we produced this bilged effect in the paper by passing the web between concave and convex rollers to stretch 25 it near its central axis and give it the desired "bilged" form.

One of the principal objects of the present invention is to provide an improved process 30 for forming the bilge of such a barrel effectively and economically and without tending to tear the paper.

In practising my present process the elements, that is, the heads and staves of the barrel are formed first of the required shape, 40 and one of the objects of the invention is to provide for trimming the staves economically to the desired dimensions.

The invention consists in the process and product described hereinafter and particularly set forth in the claims.

Figure 1 is a plan showing the form of the blanks out of which I produce the barrel staves. Fig. 2 is a cross section through the blank, upon an enlarged scale. Fig. 3 is a 45 vertical cross section taken through a press and illustrating the manner in which the blank is given the desired curved form. This section also passes through the dies which shape the blank. Fig. 4 is a longitudinal vertical section through the dies and further illustrating the manner in which

they form the staves. Fig. 5 is a plan showing the form of the blank out of which the heads of the barrel are formed. Fig. 6 is a vertical section through the head dies, and 60 illustrating the manner in which the head is formed. Fig. 7 is a cross section taken through one of the hoops and illustrating the manner in which the hoops may be formed of paper, if desired. Fig. 8 is a dia- 65 grammatic view illustrating the heating of the dies to render the staves rigid. Fig. 9 is an end-view showing a trimming table, and illustrating the manner in which the edges of the staves are trimmed while held 70 in the dies. Fig. 10 is a side elevation partly broken away to illustrate the form of the finished barrel.

In order to form one of the barrel staves, I arrange in layers a number of elongated 75 strips of stock, with a liquid adhesive between them so as to form a blank 1, as illustrated in Figs. 1 and 2. A quick drying adhesive is preferable for this purpose. While the adhesive is still wet, I place this stave 80 blank 1 between two dies, 2 and 3. The lower die 2 is of enlarged width at its base, as indicated in Fig. 3, and presents a concave upper face 4, of the desired form, which is not only concave transversely, as indicated 85 in Fig. 3, but concave longitudinally of the die as shown in Fig. 4. The upper die 3 has a convex lower face 5, which conforms to the curvature of the face 4 so that the blank 1 may be forcibly pressed or clamped 90 between the dies in such a way as to bend the strips 1^a into a curve. The longitudinal side faces 2^a of the two dies may converge 95 upwardly in the manner illustrated in Fig. 3, and these faces are in preferably radial planes from the axis of the transverse curvature, or arc of the die as seen in Fig. 3.

In order to apply the pressure, the dies are mounted in a press 6 upon a table 7, and the pressure is brought to bear on the upper 100 clamp by means of hand wheels 8, attached rigidly to power-screws 9. Near the end of the die 3, the working face 5 of the die is provided with transverse tongues or ribs 10. These tongues or ribs are intended to 105 form the croze in the staves when the pressure comes upon the dies. The blanks are preferably so long and wide that their side edges protrude from the side faces and ends of the dies in the manner indicated in Figs. 110 3 and 4. The ends of the dies have inclined end faces 11, as shown in Fig. 4. When the

pressure has been brought to bear on the dies, they may be secured together so as to maintain the pressure upon the blank by means of clamps 12 applied as indicated in Fig. 3, the upper arms of said clamps being provided with adjusting screws 13, which may be tightened by means of an ordinary wrench. The clamped dies holding the staves are then preferably placed in an oven or drying chamber, 14, as indicated in Fig. 8, and subjected to a temperature of approximately 150° F. for one hour or more. This high temperature dries the glue and the vapors and liquid may pass out from between the dies through a drain or vent 15. After the staves have been subjected to the temperature of the drying chamber 14, the edges of the dried staves which project beyond the side faces of the dies are trimmed or shaved flush with the sides of the dies by passing the dies in any suitable manner, such as between inclined rotary cutters or saws 16, as indicated in Fig. 9. These rotary cutters are attached on inclined converging shafts 18, which have bevel gears 19 meshing with driving bevel gears 20. In order to enable the dies to be passed between these cutters in the manner illustrated in Fig. 9, clamps 21, similar to the clamps 12, are applied to the ends of the dies, and a central channel or gutter 22 is formed in the horizontal part of table 23, which supports the dies as they are passed between the cutters. The rotating cutters lie close to the side faces of the dies and simply cut off the projecting edge, so as to leave the edges of the staves lying substantially in the planes of the side faces of the dies. The projecting ends of the staves are simply trimmed off with a knife flush with the end faces 11.

In order to relieve the pressure on the stave which occurs at the tongues 10 which form the croze, and to prevent weakening the stave at this point, I prefer to form slight depressions or recesses 25 transversely in the upper face of the lower die. This prevents the tongues 10 from cutting through the paper and may result in producing a slight outward set-off of the paper at this point. This off-set, however, will not be sufficient to interfere with placing the hoops upon the finished barrel. The heads of the barrels may be also formed of paper, as illustrated in Figs. 5 and 6. In forming the heads, I cut a number of blanks of circular form and arrange them in layers in the same manner as that described in forming the staves, placing a liberal quantity of liquid glue between the layers. In this way I form a circular disk or blank 26 which is built up of the several thicknesses or layers of paper. This blank is then subjected to pressure between two circular dies, 27 and 28, as illustrated in Fig. 6, the

lower die of which is dished so as to present a concave upper face 29, and the upper die 28 has a convex face 30 which conforms to the curvature of the face 29. Near their edges, these dies 27 and 28 have annular knives 31 which trim the edges of the blank and which present inclined faces 32 which form the head with a double bevel edge to fit the croze grooves of the staves. This double bevel edge is received in the croze 7 of the barrel. The middle portion of the lower die 27 is formed with a drip opening or vent 33, through which excess glue may pass and through this opening steam may escape when the heads are heated in the 85 drying chamber in the manner illustrated in Fig. 8.

The finished barrel or keg 34 is formed from the staves in the same manner as an ordinary barrel, that is they may be formed by the usual cooperage processes. The finished heads are applied preferably with the "dish" inward, that is, the convex sides of the heads are disposed inwardly. This increases the strength of the heads under pressure from the interior. The barrel staves are held in the barrel form by bands or hoops 35 applied in the usual manner. If desired, the hoops may be formed of annular waste pieces 36, liquid adhesive being placed between the layers and allowed to harden under pressure and high temperature, so as to form a built up ring or hoop 37, as illustrated in Figs. 5 and 7.

I believe that probably the central parts 100 of the layers are subjected to a considerable distorting or stretching force when the pressure is being applied by the dies. However, in order to prevent any tendency of the 105 separate layers to tear, a liberal supply of the liquid adhesive should be used. In this way the absorbent fiber of each layer are sufficiently moistened to permit of appreciably extending them to produce the bilge effect; and when the adhesive hardens, a 110 very rigid stave of the desired form results. The paper which it is preferable to employ is known as "bogus" and is particularly adapted to this purpose on account of its 115 high absorbent quality.

The drying of the staves by means of heat is preferable because it saves time in the 120 drying, but a very serviceable stave can be made even if the staves are kept in the dies a very short time and are then permitted to dry in the air. They will substantially maintain the shape into which they have been pressed and the stave will become substantially as good as such staves when dried by heat.

It is understood that the embodiment of 125 my invention described above is only one of the many modifications or forms the invention may take, and I do not wish to be limited in the practice of the invention nor in my claims to the embodiment set forth above. 130

What I claim and desire to secure by Letters Patent is:

1. The process of producing barrel staves which consists in forming a blank of a plurality of strips of an absorbent substance, placing a liquid adhesive between said layers to saturate the fibers thereof, pressing said blank between dies into the curved form of a stave with the edges of the blank projecting beyond the side faces of the dies, and then trimming the projecting edges of said blank.
2. The process of forming a barrel stave which consists in forming a blank of a plurality of layers with a moist adhesive between said layers, applying pressure by pressing the blank between dies to curve the same, and permitting the adhesive to dry.
3. The process of making a barrel stave which consists in producing a blank of separate layers with an adhesive between said layers, curving said blank and forming crozes in the face thereof by pressure.
4. The process of forming a barrel element which consists in forming a blank of said element of a plurality of layers with a moist adhesive between said layers, pressing said blank into curved form and drying said adhesive while the curved form of said blank is maintained.
5. A barrel stave formed of a plurality of layers of blanks of longitudinal and transverse concave form and connected together by an adhesive.

Signed at New York in the county of New York and State of New York this 25th day of March A. D. 1912.

ERNEST P. EVERETT.
